UNITED STATES PATENT OFFICE.

EDWARD R. LINEBAUGH AND MARTIN H. STENDER, OF BARBERTON, OHIO, ASSIGNEES
TO THE DIAMOND MATCH COMPANY, OF CHICAGO, ILLINOIS, A CORPORATION OF
ILLINOIS.

INKING MECHANISM FOR PRINTING PRESSES.

Application filed May 4, 1923. Serial No. 636,548.

To all whom it may concern:

Be it known that we, EDWARD R. LINEBAUGH and MARTIN H. STENDER, citizens of the United States, and residents of Barberton, in the county of Summit and State of Ohio, have invented certain new and useful Improvements in Inking Mechanism for Printing Presses, of which the following is a specification.

10 This invention relates to inking mechanism for printing presses, and more especially the kind of presses wherein associated inking and distributor rollers are cooperatively arranged in relation to an ink-distributing disk and a type form. In presses of the kind mentioned the distributor roller is mounted to rotate in peripheral contact with a pair of inking rollers, and the associated rollers are borne by a swinging frame which 15 is so constructed and arranged as to carry the rollers through a path wherein the inking rollers travel upon the type form and the inking surface of the disk. The distributor roller has combined therewith screw 20 and nut mechanism which is constructed and actuated to impart a single longitudinal impulse to the roller during each succeeding stroke of the associated rollers in order to effect the distribution of the ink on the 25 peripheries of the inking rollers. Such mechanism is expensive; it requires nice fitting and adjustment, and it soon gets out of order.

The object of our invention is to provide a motion transmitting mechanism of simple 30 and efficient construction between the swinging frame and the distributor roller, whereby several longitudinal impulses are imparted to the distributor roller during each succeeding stroke of the frame, and in consequence a better distribution of the ink on the inking rollers than formerly is accomplished, as will be hereinafter described and claimed.

In the drawings—

Figure 1 is a side elevation, partially in dotted outline, of a portion of a style of printing press equipped with inking mechanism embodying the principle of our invention.

Fig. 2 is an enlarged view of one end of 50 the associated ink distributor and inking rollers, and their connections with the swinging frame.

Fig. 3 is a plan of said rollers and connections.

Fig. 4 is a vertical section through one of 55 the saddles, and its adjuncts, as on the line 4—4 of Fig. 2.

Fig. 5 is a longitudinal section of one end of the distributor roller and of its shaft, showing one of the adjustable end stops for 60 the roller.

Fig. 6 is a perspective view of the distributor roller and its shaft.

Fig. 7 is a similar view of one end of the 65 associated rollers and their supporting saddle, showing the bell-crank connection which is included in the mechanism for reciprocating the distributor roller.

Referring to the drawings, 10 designates the stationary main frame of a typical printing press, and 11 the oscillatory bed frame thereon, which latter frame supports the type-form at 12; and also the relatively inclined ink-distributing disk 13 and the inking devices and their appurtenances. Such 70 inking devices include an ink fountain 14 arranged to overhang the upper path of the disk; a roller 15 for said fountain; a pair of inking rollers 16; a distributor roller 17 in peripheral contact with the latter, and a single inking roller 18 below the roller 16. The 75 rollers 16 are borne in spaced parallel relation to each other by saddles 19 which are located at each side of the press. Each saddle is pivotally connected to the outer end of 80 a longitudinally reciprocative rod 20 that is 85 slidably mounted on the adjacent side member 21 of a swinging frame pivotally supported on the bed frame 11. Only one of the saddles and its operating rod are shown. 90 The lower roller 18 is supported at each end by a hook saddle 22 which is also connected with a reciprocative rod 23 mounted in the adjacent frame member 21. The rods 20, 23 95 are normally retracted by means of suitably disposed springs, as 24, thereon, and the various elements are so co-operatively arranged that during the oscillation of the frame 21 the respective saddles and their 100 rollers are swung upwardly and rearwardly and back again in such a manner that the inking rollers traverse the type-form and the inking surface of the disk. The upper roller of the pair as it reaches the limit of its rearward movement impinges against the fountain roller 15 and takes ink therefrom,

which ink in the next succeeding forward movement of the frame 21 and its accessories

is transferred to the rollers 16, which, in turn, distribute the ink on the surface of the disk.

In the oscillatory travel of the roller-carrying frame 21 the inking rollers are maintained in yielding contact with the opposing type-form and with the inking surface of the disk, by the retractive force of the springs on the respective rods 20, 23, said rods being longitudinally moved in the respective frame members in accordance with the varying outward and inward distances of the rollers in respect to the axis of oscillation of the frame. The foregoing described mechanism being generally old, it requires no detailed description herein.

In the preferred form of our invention herein illustrated the distributor roller 17 is loosely mounted on a shaft 25 having at each end a polygonal end portion 26 which is mounted in a bearing bracket 27 on the adjacent saddle 19. The roller 17 is adjustably positioned for rotation on the shaft by end stops comprising split screw heads 28 which are clamped on the shaft and at the respective ends of the roller by means of nuts 29 on the heads. The bracket 27 has an opening therethrough which receives the end portion of the shaft, such opening being of appropriate size and form to permit movement of the shaft transversely as well as longitudinally of its axis. In the bracket is a suitably-disposed plunger 30 which is pressed against the opposed shaft portion 26 by the confined spring 31, the distributor roller thus being held yieldingly in peripheral contact with the inking rollers 16. One end of the shaft is provided with a bifurcated member 32 which embraces an arm 33 of a bell-crank lever and thus constitutes a lever engaging member. This lever is fulcrumed, as at 34, on a block member 35 loose on an elongated pivot stud 36 which connects the adjacent saddle 19 with its rod 20. Loose on the stud is one end of a link 37 which is pivotally connected at its opposite end to a rock-arm 38, fulcrumed, as at 39, on the adjacent frame member 21. The rock-arm is connected by means of a link 40 with the other arm, 41, of the bell-crank lever, which link is preferably made in two parts adjustably connected by means of a screw turn-buckle 42.

The foregoing described lever and link connections constitute motion transmitting mechanism between the swinging frame and the distributor roller, whereby, during the effective travel of the said frame and the resulting longitudinal reciprocation of the rod 20 having the elongated stud connection with the adjacent saddle 19, the rock-arm 38 is oscillated and the motion is positively transmitted therefrom by means of the link 40 to the crank-lever, which lever, in turn, effects longitudinal reciprocation of the distributor

roller upon the peripheries of the inking rollers 16. Owing to the various longitudinal movements of the rod 20 during its travel with the frame member 21 several reciprocative impulses of the distributor roller along the inking rollers are effected, such impulses, in the construction illustrated, being four times as often as when the distributor roller is moved by the screw and nut devices previously employed, and, in consequence, a better distribution than formerly of the ink is ensured, which result is particularly desirable on jobs requiring heavy inking.

It is to be noted that the acting arm 33 of the bell-crank lever is made relatively broad to ensure its continued effective engagement with the bifurcated member 32 at various points and thus compensate for the different angular positions assumed by such arm and the roller-bearing saddle during their travel with the frame 21.

Our invention is not limited to the specific details of construction herein disclosed as the mechanism may be modified within the principle of the invention and the scope of the appended claims.

We claim—

1. Inking mechanism for printing presses, including associated inking and distributor rollers, a support for the said rollers, a swinging frame, a reciprocative connection between the said support and frame, and motion transmission mechanism between the said frame and the distributor roller, whereby by the said roller is longitudinally reciprocated during the travel of the frame.

2. Inking mechanism for printing presses, including associated inking and distributor rollers, a support for the said rollers, a swinging frame, a reciprocative connection between the said support and frame, and link and lever connections between the said frame and the distributor roller, whereby the said roller is longitudinally reciprocated during the travel of the frame.

3. Inking mechanism for printing presses, including associated inking and distributor rollers, the distributor roller having its shaft extended and provided with a lever-engaging portion, a support for said rollers, the extended end of the shaft being slidably mounted in said support, a swinging frame, a reciprocative rod connection between the said support and frame, and motion transmission mechanism between the said frame and distributor roller, said mechanism including a bell-crank co-operating with the lever-engaging portion of said shaft.

4. Inking mechanism for printing presses, including associated inking and distributor rollers, the distributor roller having its shaft extended and provided with a lever-engaging portion, a support for the said

rollers, the extended end of the shaft being mounted for transverse as well as longitudinal movement in the said support, spring pressure means acting on the said shaft to 5 maintain the distributor roller in peripheral contact with the inking rollers, a swinging frame, a reciprocative connection between the said support and frame, and link and lever connections between the said 10 frame and the distributor roller, whereby the said roller is longitudinally reciprocated during the travel of the frame.

5. Inking mechanism for printing presses, including associated inking and distributor 15 rollers, the distributor roller having its shaft extended and provided with a lever-engaging portion, a support for the said rollers, the extended end of the shaft being slidably mounted in said support, a swinging 20 frame, a reciprocative rod connection between the said support and frame, a rock-member on the frame, a link connection between the said member and the roller support, a crank lever mounted on the said support, and having one arm co-operating with 25 the lever-engaging portion of the said shaft, and a link connection between the other arm of the said crank lever and the rock member.

6. Inking mechanism for printing presses, 30 including associated inking and distributor

rollers, a support for the said rollers, a swinging frame, a reciprocative rod connection between the said support and frame, a rock-member on the frame, a link connection between the said member and the roller support, a crank lever mounted on the said support, a link connection between one arm of the said crank lever and the rock-member, and operative connection between 35 the other arm of the crank lever and the distributor roller. 40

7. Inking mechanism for printing presses, including associated inking and distributor rollers, a saddle in which the said rollers are mounted, a swinging frame, a reciprocative rod in the said frame, a stud pivotally connecting the outer end of the rod and the saddle, a rock arm on the frame, a link connection between the said arm and the stud, a member loose on the said stud, 45 a bell-crank fulcrumed on the said member and having one arm co-operating with the lever-engaging portion of the said shaft, and a link connection between the other arm of the crank lever and the rock arm. 50

Signed at Barberton, in the county of Summit and State of Ohio, this 30 day of April A. D. 1923.

EDWARD R. LINEBAUGH.

MARTIN H. STENDER.
